UNITED STATES PATENT OFFICE.

WINIFRED VIOLET REDFERN AND ALFRED EDWARD REDFERN, OF VICTORIA, BRITISH COLUMBIA, CANADA.

LINE-SPACE AND CARRIAGE-RETURN LEVER AND PAD FOR TYPEWRITERS.

Application filed July 10, 1922. Serial No. 574,249.

To all whom it may concern:

Be it known that we, WINIFRED VIOLET REDFERN and ALFRED EDWARD REDFERN, citizens of Canada, residing at Victoria, in the Province of British Columbia, in the Dominion of Canada, have jointly invented a new and useful Improvement in the Line-Space and Carriage-Return Levers and Pads for Typewriters, and do hereby declare the following to be a specification of the same.

The improvement relates to the finger piece of the line space and carriage return lever of a typewriter.

15 The purpose of this improvement is to furnish a cushion on the face of the finger piece of a line space and carriage return lever of a typewriter, preventing bruising of the fingers when the typewriter is in use.

20 Similar letters refer to similar parts throughout the several views.

Figure 1 shows a front view of the pad in place on the finger piece of the improved line space and carriage return lever of a typewriter.

25 Dotted line E indicates the outline of the outside edge of that portion of the finger piece behind the rubber.

The approximate position of the inside edge of the rim or flange is shown by dotted line F.

30 Dotted line G indicates the approximate extent of the depression under the rim or flange.

35 Figure 2 is a side view of the finger piece of the lever with the pad in place.

Figure 3 is a section on the line A, B, Fig. 1, of the finger piece and pad.

40 Figure 4 shows the finger piece of the lever without the pad.

Figure 5 is a side view of the finger piece of the lever without the pad.

Figure 6 is a section on the line A, B, Fig. 4.

Figure 7 is an outline of the pad.

45 Figure 8 is a section on the line C D, Fig. 7.

Figure 9 is a section on the line A B, Fig. 7.

The improved line space and carriage return lever comprises a finger piece having a raised rim around the sides and a depression inside the rim. A rubber pad covering the face of the finger piece is fitted into the depression; and is held in place by a shoulder which projects into the cavity under the rim of the finger piece. The pad may be made additionally secure by the use of cement or other adhesive mixture; but if only held in place by the rim it may easily be replaced when worn out. The rim need not go completely around the finger piece, but would vary for different shapes of finger pieces.

What we claim as our invention and desire to secure by Letters Patent is:—

In a line space and carriage return lever of a typewriter, said lever having a thumb or finger engaging portion: an undercut recess in said portion and a resilient member 70 having a pad to overlie said thumb or finger engaging portion and an integral lug corresponding to the recess and adapted to be received thereby.

In testimony whereof, we have signed 75 our names to this specification in the presence of two subscribing witnesses.

Victoria, B. C., May 13th, 1922.

WINIFRED VIOLET REDFERN.
ALFRED EDWARD REDFERN.
